ANTI-RECOIL GUN BARRELS

John F. Mutter, Pendleton, Oreg.

Application February 10, 1956, Serial No. 564,711

2 Claims. (Cl. 89—14)

This invention relates to new and useful improvements and structural refinements in firearms, particularly rifles, revolvers, pistols, and the like, and the principal object of the invention is to effectively counteract the customary recoil occurring when the gun is fired and to simultaneously counteract the so-called muzzle flip, or tendency of the muzzle to rise upon firing.

More specifically, the instant invention is an improvement of my earlier invention disclosed in my co-pending application Serial No. 473,652, filed December 7, 1954, now Patent No. 2,842,024, of which this application is a continuation-in-part.

While experimenting with and using the invention according to my earlier application, I found that the same lends itself to certain structural simplifications on one hand, and certain functional refinements on the other. Accordingly, the instant application discloses certain variations of my earlier invention, in which such improvements are embodied.

Briefly stated, one important feature of the present invention resides in embodying the anti-recoil means integrally in the gun barrel rather than as an attachment thereto.

Another important feature involves the provision of an anti-recoil gas chamber in the gun barrel which chamber is only slightly larger in diameter than the bore of the barrel and does not require the use of a gas baffle or trap, but only a close sealing bullet exit.

Another important feature of the invention resides in providing a sleeve or a plurality of sleeves coaxially on the muzzle portion of the barrel and forming the latter as well as the sleeves with sets of gas outlet openings arranged alternately in diametrically opposite regions thereof, so as to provide a tortuous passageway for escape of gasses from the gas chamber in the muzzle portion to the atmosphere.

With the above more important objects and features in view and such other objects and features as may become apparent as this specification proceeds, the invention resides in the arrangement of parts and details of constructions substantially as shown in the accompanying drawing, wherein like characters of reference are employed to designate like parts and wherein:

Figure 1 is a fragmentary longitudinal sectional view of a gun barrel embodying the invention integrally therein;

Figure 2 is a cross-sectional view, taken substantially in the plane of the line 2—2 in Figure 1;

Figure 3 is a cross-sectional view, taken substantially in the plane of the line 3—3 in Figure 1;

Figure 4 is a fragmentary sectional detail, taken substantially in the plane of the line 4—4 in Figure 3;

Figure 5 is a fragmentary longitudinal sectional view showing a modified form of the invention;

Figure 6 is a cross-sectional detail, taken substantially in the plane of the line 6—6 in Figure 5;

Figure 7 is a fragmentary longitudinal sectional view of another modified form of the invention;

2

Figure 8 is a cross-sectional detail, taken substantially in the plane of the line 8—8 in Figure 7;

Figure 9 is a fragmentary longitudinal sectional view of another modified form of the invention; and

5 Figure 10 is a cross-sectional detail, taken substantially in the plane of the line 10—10 in Figure 9.

Referring now to the accompanying drawing in detail, particularly to Figures 1—4 thereof, the gun barrel is designated generally by the reference numeral 25, including the bore 26, the muzzle 27 and the usual front sight 28.

The muzzle portion 27 of the barrel is formed with a diametrically enlarged gas chamber 29 provided at its front end with a bullet sealing exit 30, which is spaced forwardly from but is coaxial with the bore 26 of the barrel.

The muzzle portion 27 is also provided at the top thereof with a plurality of rows of gas outlet openings 19, these openings, as in my earlier application, being spaced laterally or circumferentially to opposite sides of the vertical medial line of the barrel and the openings in each row having their axes radially disposed.

The openings 19 communicate with the gas chamber 29 to facilitate escape of exploded gases therefrom and, of course, the size and number of the openings is such as to properly control the flow of gases escaping therethrough and produce the required amount of downward thrust to effectively counteract muzzle flip.

The portion of the barrel 25 rearwardly of but adjacent to the gas chamber 29 is provided at the top thereof with rows of ventilating apertures 21, there preferably being two rows of such apertures spaced laterally to opposite sides of the vertical medial line of the barrel and communicating with the bore 26. The axes of the apertures 21 are disposed in radial planes, but are inclined rearwardly as shown in Figure 4, so that gases escaping therethrough are rearwardly directed. This embodiment of the invention is integral with the barrel of the gun, rather than being an attachment thereto, as in my earlier application.

The modified form of the invention shown in Figures 5 and 6 is similar to that in Figures 1—4, except that the gas chamber 31 is in the form of a counterbore only slightly larger in diameter than the bore 26a and extending freely to the front end of the barrel so that the gas baffle or trap at the front of the barrel is not necessary. The ventilating apertures 21 may be also omitted in this form of the invention.

The principle of braking is to suddenly arrest the forward flow of high velocity, high pressure gases while the bullet momentarily seals off the exit, and forcing these gases to pass out at a neutral angle, thus effectively controlling gas acceleration recoil and rocket effect of otherwise liberated and expanding gases at the muzzle, such as occurs in unbraked barrels.

In another modified form shown in Figures 7 and 8, the barrel 32 has the muzzle 33 reduced in outside diameter and formed with a central gas chamber 34 which is larger in diameter than the bore 35. A cylindrical sleeve 36 is positioned coaxially in spaced relation on the muzzle 33, this being effected by providing the muzzle at its inner end portion and the sleeve with engaging screw-threads 37. It will be apparent from the foregoing that an annular gas chamber 38 exists between the muzzle portion 33 and the sleeve 36, the front end of this chamber being closed by an inturned flange 39 provided on the sleeve and engaging the muzzle.

The outer surface of the sleeve 36 is flush with the outer surface of the barrel 32 and the muzzle portion 33, in this instance, is formed at the bottom thereof with the gas escape openings 19a which establish communication between the central chamber 34 and the annular

chamber 38. Similar openings 19b are provided in the top portion of the sleeve, to establish communication between the annular chamber 38 and the atmosphere. In this manner, the openings 19a, 19b coat with the chamber 38 to provide a tortuous outlet passageway for gases from the central chamber 34 and since the openings 19b communicating with the atmosphere are disposed at the top of the sleeve, downward thrust will be produced to counteract muzzle flip, as in the embodiments of the invention already described.

An outwardly flanged, externally screw-threaded bushing 40 is provided in the muzzle portion 33 at the outer end of the central chamber 34 and affords a bullet guide or exit 40' in axial alignment with the bore 35.

Another modified form of the invention shown in Figures 9 and 10 is similar to that in Figures 7-8, with the exception that a plurality of sleeves 36a, 36b are positioned coaxially and in radially outwardly spaced relation on the muzzle portion 33a of the barrel 32a. This construction is feasible in instances where the barrel is of sufficient diameter to accommodate the plurality of sleeves, while maintaining the outermost sleeve flush with the outside of the barrel.

The sleeves 36a, 36b are connected by screw-threads 37a, 37b to the respective, diametrically stepped, screw-threaded portions of the barrel as illustrated in Figure 9 and coat with the muzzle portion 33a in providing a plurality of annular gas chambers 38a, 38b, which are closed at their forward ends with inturned flanges 39a, 39b, as will be clearly apparent. The muzzle portion 33a, in this instance, may also assume the form of a sleeve connected to the main body of the barrel by screw-threads 41 at its rear end, and formed with an integral bullet guide or exit 42 at its front end.

The gas escape openings 19, 19a, 19b are provided alternately in diametrically opposite regions of the muzzle portion and sleeves, that is, the openings are at the bottom of the inner sleeve but at the top of the muzzle portion and outer sleeve, to form a tortuous passageway for the gases. In all instances the openings are at the top of the outermost sleeve, so that gases escaping therefrom into the atmosphere create the necessary thrust to counteract muzzle flip.

In both forms of the invention shown in Figures 7 and 9, the size and number of the openings is such that the combined area of the openings in the muzzle portion or innermost sleeve is smaller than in the next outer sleeve, with the combined area of the openings in the outermost sleeve being the largest, whereby to facilitate rapid reduction in gas pressure by the time the bullet leaves the exist of the muzzle.

In the construction shown in Figure 7, the muzzle portion 33 may also be formed separately from the barrel in the nature of a sleeve such as is illustrated in Figure 9, in which event the exit bushing 40 may be

omitted and the bullet exit formed integrally in the separate sleeve.

While in the foregoing there have been shown and described the preferred embodiments of the invention, various other modifications may become apparent to those skilled in the art to which the invention relates. Accordingly, it is not desired to limit the invention to this disclosure and various modifications may be resorted to, such as may lie within the spirit and scope of the appended claims.

What is claimed as new is:

1. An anti-recoil gun barrel having a muzzle portion provided with an enlarged central gas chamber, and a cylindrical sleeve provided on said barrel coaxially with and in radially outwardly spaced relation from the muzzle portion thereof whereby to form an annular gas chamber between the muzzle portion and said sleeve, said central gas chamber having a lateral wall with imperforate top and sides and a bottom provided with a set of gas outlet openings communicating with said annular gas chamber, said annular gas chamber having a lateral wall with imperforate sides and bottom and a top provided with another set of gas outlet openings, whereby to provide a tortuous gas passageway extending radially outwardly from said central chamber to the atmosphere.
2. An anti-recoil gun barrel having a muzzle portion provided with an enlarged central gas chamber, and a plurality of cylindrical sleeves provided on said barrel coaxially with and in radially outwardly spaced relation from the muzzle portion and from one another whereby to form a plurality of annular gas chambers between the sleeves and between the innermost sleeve and the muzzle portion, said muzzle portion and said sleeves being provided alternately at diametrically opposite regions thereof with sets of gas outlet openings and the remaining regions thereof being imperforate, whereby to provide a tortuous gas passageway extending radially outwardly from said central chamber to the atmosphere.
